JACQUES J. HARDIN, OF BELLINGHAM, WASHINGTON.

HEATING-STOVE.

1,192,190.

Specification of Letters Patent. Patented July 25, 1916.

Application filed June 16, 1915. Serial No. 34,338.

To all whom it may concern:

Be it known that I, JACQUES J. HARDIN, a citizen of the United States, and a resident of Bellingham, in the county of Whatcom and State of Washington, have invented certain new and useful Improvements in Heating-Stoves, of which the following is a specification.

My invention relates to improvements in heating stoves; and the primary object of my invention is to make a stove in which the fuel is burned at greater efficiency than is usually possible, while some of the secondary objects are to make a sectional stove so that it can be enlarged by adding more sections, and also, one that can be closely regulated to produce varying amounts of heat as desired.

The apparatus by which I attain these objects is illustrated in the accompanying two sheets of drawings in which—

Figure 1 is a front elevation of my stove, Fig. 2 a rear elevation of the same, Fig. 3 a side elevation broken away transversely and partly in section on the line A B of Fig. 5, Fig. 4 an elevation of the left-hand constituent section 1 as seen from the right, and having the front plate of the stove in place, which is also broken away transversely and of which one half is shown in cross section on the dotted line x—y of Fig. 3, and Fig. 5 is a plan view, and Fig. 6 is a perspective view of the firepot portions of two sections broken away from the remaining portions of said sections.

In some of the views certain parts are omitted or broken into in order to show other parts hidden thereby.

In all of the views similar characters refer to similar parts.

The stove illustrated comprises the four similar sections or units 1, 1, 1, 1, the front plate 2 and back plate 3. Each section, as best shown in Fig. 4, is symmetrical about a medial, vertical plane and comprises a central space 1^e, and a lower space 1^h separated from the central space by the partition 1^g. The space 1^e is embraced by two vertical, return, radiator, smoke flues the return ends of which communicate with a dome chamber 1^l. The up flue 1^c of each of said vertical, return flues leads from said lower space 1^h,

and the down flue 1^b of each of the same leads into a section of a horizontal, radiator, smoke flue 1^d. Said up and down flues are 55 separated by the partitions 1^a, 1^a. When several of the sections 1, and front and back plates 2 and 3, are fastened together by bolts 11, 11, 11, through registering holes as shown in Figs. 1, 2, 3 and 5, the central 60 spaces 1^e are joined and inclosed to constitute a fuel and gas magazine, and the lower spaces 1^h form the ashpit of the stove. Also the two, short, horizontal radiator flues 1^d, 1^d, in each section, register and form two 65 horizontal flues connecting the lower ends of the down flues 1^b, 1^b, 1^b, 1^b on each side of the stove, while the up flues 1^c afford communication between the ashpit 1^g and said horizontal flues 1^d, 1^d, etc., through 70 down flues 1^b, 1^b, etc. Furthermore the partitions 1^g unite to form a continuous fire pot. Each section of this firepot, Fig. 4, is protected by a lining 12 of same width. Registering grooves or serrations 12^a, 12^a, 75 etc., are made in the edges of both the firepot and lining 12. These are of graded widths diminishing from the lower part of the firepot toward its upper parts where they are quite small. In the assembled stove 80 these grooves face each other in the juxtaposed edges of 1^g, 1^g, etc., and constitute grate openings which furnish the only means of communication between the ashpit and the magazine. Beneath the firepot is placed 85 the ash-pan 8, Fig. 3. The front plate 2 is provided with the fuel chute 4 and the draft flue 4^c covered by housings 2^a and 2^b. Also there are two openings 2^c through plate 2 entering the ashpit 1^h from the bifurcated 90 lower ends of flue 4^c. Plate 2 is further furnished with holes registering with horizontal flues 1^d, 1^d which are covered by thumb-screw-retained caps 2^f, 2^f. Also there are the holes 2^d and 2^e, the former closed by 95 thumb-screw-retained cap 2^e and affording an entry into the firepot space and is used in the removal of clinker, while the latter is closed by hinged, ashpit door 7. In addition to bolts 11, the plates 2 and 3 are secured by cap screws as illustrated.

The back plate 3 is provided with smoke hole 3^d providing a smoke outlet from the lower part of the magazine 1^e into stack

pipe 10, and also two holes registering with horizontal flues 1^a, 1^d and communicating with smoke flue 3^l. Said flue 3^l covered by housing 3^a affords communication between 5 horizontal flues 1^a, 1^d and smoke pipe 10. A damper 3^b to close hole 3^a is installed under housing 3^a on damper shaft 3^c. A rectangular hole is provided in the lower 10 part of housing 3^a through which said damper is introduced. This hole is not illustrated but is shown as closed by cover 3ⁿ. Damper shaft 3^c is mounted for sliding endwise in bearings in said cover 3ⁿ and in the upper end of housing 3^a. The shaft 3^c 15 is attached to damper 3^b by bearings 3^h. These bearings permit the rotation of said shaft. Lugs 3ⁱ on said shaft, prevent endwise movement of said shaft relative to the damper. The lower end 3^f of the damper 20 shaft 3^c is bent over at right angles and can engage with one of lugs 3^g. A cold handle 3^e is attached to the upper end of the damper shaft. To operate this damper the handle 3^e is turned to a position at right 25 angles to the plate 3 when the end 3^f is disengaged from a lug 3^g. Then the damper can be moved to its dotted-outline position and retained there by turning said handle and the shaft 3^c so that the end 3^f engages 30 with the lowest one of lugs 3^g. Then the damper is fully opened. Said damper can be retained in any of several intermediate positions between the fully closed position, shown in full lines, and the fully-opened 35 position described by engaging the end 3^f with one of the several intermediate lugs 3^g. Damper 3^b is carefully seated and must make a gas-tight closure of hole 3^a. By gas-tight closure or a seal is meant a closure 40 that will be sufficiently tight to substantially prevent the leakage of gas under the pressure existing in the fuel magazine during normal operation.

The upper end of housing 2^a is in the 45 same plane as the upper end of fuel chute 4. These ends are carefully surfaced. Both are closed with the hinged cover 5, which can be tightly clamped on by thumb-screws 6, 6. This cover is fully shown in Figs. 4 50 and 5 but broken off in Fig. 1 in order to more clearly show the structure beneath. The walls of the upper part of draft flue 4^c comprise housing 2^a, the front wall of chute 4, two partitions 4^b, 4^b, which connect 55 the sides of said chute and said housing, and a partition 4^a parallel with and between the tops of said chute and said housing and a short distance below said top. The cover 5 is perforated with holes 5^b in a circle about 60 a central pivot 5^d. The holes 5^b open into the flue space 4^c around chute 4. A cap 5^a is retained on cover 5 by pivot 5^d and may revolve on said pivot. Cap 5^a has a set of holes 5^c normally registering with holes 5^b

in cover 5. Two of each set of these registering holes 5^b and 5^c are clearly shown in Fig. 3. By turning cap 5^a through a partial revolution about pivot 5^d the openings 5^b through cover 5 can be more or less completely closed. The stove finds suitable supports in legs 9.

The operation of this stove is as follows: The magazine 1^e is filled with fuel through chute 4. Hinged cover 5 is tightly clamped down by screws 6, 6 making a gas-tight 75 closure. Damper 3^b is fully opened. The fuel is ignited through grate openings 12^a. The openings 5^b through flue cover 5 into draft flue 4^c are fully opened. The fuel now burns under direct draft. After the fuel in 80 the fire pot is thoroughly ignited damper 3^b is fully and tightly closed, as are also all other openings except draft holes 5^b which remain open. During the operation of the stove under direct draft the air was expelled from the magazine 1^e and replaced with the products of combustion. With the damper and the stoke hole tightly closed as described, no gases can enter or leave the magazine except through the firepot 85 openings 12^a. But since air can at all times pass from the ashpit 1^h through flues 1^c, 1^b, 1^a and 3^l into stack pipe 10, it therefore enters the open draft 5^b and fills the ashpit and must pass closely by the grate openings 90 12^a in order to enter flues 1^c on its way to the chimney to which the stack pipe 10 is connected. Hence the firepot is suspended, as it were, in air and the combustion already started in the firepot, as described, 95 will draw on this air in the ashpit for support and said combustion will continue in a slow way until the producer gas generated thereby and accumulating in the magazine 1^e has sufficient pressure to flow downward 100 through the burning fuel in the firepot where it is burned, and the hot, incombustible products of this burning pass downward through openings 12^a into the ashpit and from thence together with the surplus of 1 said draft air through flues 1^c, 1^b, 1^a and 3^l into the stack pipe 10. A quantity of these hot gases will fill the upper parts 1^f of the radiating flues and give up a portion of their heat to the radiating surfaces inclosing the same, and other portions of said heat will be absorbed from said gases by the radiating walls of the flues 1^b as they pass downward therethrough. The progress of the combustion of the fuel in the firepot 11 can be controlled by the rate of admission of air through the draft holes 5^b.

Of course, a portion of the producer gas generated by the slow combustion passes directly from the firepot through openings 12^a in the same and thus escapes the second burning. But these openings, especially in the upper part of the pot are small in order

to reduce the amount thus escaping the second burning to the minimum.

In case a tight closure should not, on occasion, be made by hinged cover 5 over fuel chute 4, the producer gas escaping here will be carried downward by the draft air through the flue of housing 2² and thus ultimately pass into the smoke pipe without having escaped into the room.

It may now be understood that my new process of burning fuel for domestic purposes requires that the combustion be conducted on a grate in the bottom of an otherwise tightly closed chamber and that this combustion comprises the primal burning of the fuel to generate producer gas and also the subsequent burning of this gas on the same grate where it was generated. The successful continuance of this slow, primal burning and the subsequent burning of the gas dependent thereon—which constitute complete combustion—requires that all outlets from said chamber, except said grate, be kept tightly closed during normal operation. Also, that in order to support this slow, dual combustion on said grate, the draft air must be caused to pass closely by said grate.

After this detailed description of my stove and its operation it will be noted that it constitutes a radiator inclosing a producer-gas generator and burner and therefore is well adapted to burn fuel and radiate heat from said combustion under conditions favorable for efficiency.

Having thus described my invention what I claim to be new and desire to secure by Letters Patent is,

1. In a stove of the character described, the combination of a fuel magazine having a stoke hole and also a smoke outlet opening into a stack flue, a cover making a gas-tight closure of said stoke hole during normal operation of said stove, a damper seated over said smoke outlet making a gas-tight closure of the same during normal operation of said stove, a firepot continuous with the lower end of said magazine and having grate openings in its bottom, an ashpit beneath said firepot, a smoke flue connecting said ashpit with the stack flue, and controllable means of admitting ambient air into said ashpit.

2. In a stove of the character described, the combination of a fuel magazine having a stoke hole and also a smoke outlet opening into a smoke pipe, a cover making a gas-tight closure of said stoke hole during normal operation of said stove, a damper seated over said smoke outlet making a gas-tight closure of the same during said normal operation, a firepot continuous with the lower end of said magazine and having grate openings in its bottom, an ashpit beneath

said firepot, vertical radiator-flues leading 65 upward from said ashpit to a chamber on top of said magazine, vertical radiator flues leading downward from said chamber to a smoke flue, a smoke flue leading from said downward flues into said smoke pipe, and 70 controllable means for admitting ambient air into said ashpit.

3. In a stove of the character described, the combination of a plurality of similar vertical units each comprising a section of a fuel 75 magazine, firepot, ashpit, also two vertical, return, radiator, smoke flues, the lower end of each up flue of which connects with said ashpit section and the lower end of each down flue of which connects with a section 80 of a horizontal, radiator, smoke flue, and said horizontal radiator flue sections; a front plate having a stoke hole, with a tightly closable cover, leading into said fuel magazine, a controllable draft flue leading 85 into said ashpit and an ashpit door; a back plate having a tightly closable smoke outlet leading from said fuel magazine into a smoke flue, and said smoke flue leading from said horizontal flues and from said smoke 90 outlet into a smoke pipe; and means to fasten said vertical units and said front and back plates together.

4. In a stove comprising a plurality of similar, vertical units, each having a section of a fuel magazine, firepot and ashpit, fastened between front and back end plates, the combination of a plurality of said similar, vertical units; two sections of horizontal, radiator, smoke flues in each of said units; two vertical, return, radiator, smoke flues embracing said fuel magazine and firepot sections in each of said units, the up flue of each of said return flues connected 100 with said ashpit section and the down flues of the same leading into said horizontal-flue sections; said front plate having a stoke hole chute leading into said fuel magazine, an ashpit door, and a draft flue leading into said ashpit, the top of which surrounds said stoke hole chute, and a cover which makes a tight closure of said stoke hole chute and a controllably variable closure of said draft flue; said back plate having a tightly closable smoke outlet leading from said flue 105 magazine into a smoke flue, and said smoke flue leading from said horizontal flues and said smoke outlet into a smoke pipe; and means to fasten said vertical units and said front and back plates together.

5. In a stove comprising a plurality of similar, vertical units, each having sections of a fuel magazine and ashpit, said units fastened together in operative relation with front and back end plates, the combination 115 of said plurality of similar, vertical units; two sections of horizontal, radiator, smoke flues in each of said units; two vertical, re-

turn, radiator, smoke flues in each of said units, each leading into one of said horizontal flue sections; said front and back end plates; and means to fasten said similar, vertical units between said end plates in operative relation.

Signed at Bellingham in the county of

Whatcom and State of Washington this 9th day of June A. D. 1915.
